POSITIONING JIG FOR TUBE EXPANDER TOOL HOUSING

Thomas E. Burden, Parma, Ohio, assignor to The Standard Oil Company, Cleveland, Ohio, a corporation of Ohio

Application July 31, 1952, Serial No. 302,012

4 Claims. (Cl. 153—82)

In securing tubes in header boxes by roller expansion a manually controlled motor-driven roller is commonly used. Adequacy of union of the tube end with the header and uniformity of results from tube to tube depend upon the accuracy and effectiveness of locating and holding the rolling instrument in the tube, and this factor has been a problem in such tube apparatus as oil conversion furnaces, boilers, heat exchangers and the like. The roller should be accurately directed but its control should not be made so completely mechanical as to take away from the operator the "feel" of the device as the rolling-in operation proceeds. A skilled operator can judge the conditions and progress in any instance particularly closely by the "feel" of the roller head in action. In the present invention this faculty is retained fully available, but the operator is relieved of the laborious effort of holding the roller against possibility of lateral jumping and deviation. And a construction is had which is compact, and is not over-complicated. Other objects and advantages will appear from the following description.

To the accomplishment of the foregoing and related ends, said invention then comprises the features herein-after fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a perspective view of construction in accordance with the invention; and

Fig. 2 is a horizontal sectional view taken on a plane just above the members 7 and 8 in Fig. 1.

With a header box and tubes to be united thereto, a guide or jig in conjunction with a motor-driven roller is assembled with and anchored to the adjacent structure. In illustration, as applied to an oil-heater, there is shown in the drawing a header box 2 with tubes 3, the header box being joined to and adjacent the heating furnace wall 4, the details of that structure being immaterial, and the tube roller with its mandrel housing 5 and driving-motor 6 is positioned in a guide made up of support members 7, 8 which are joined together by a hinge-type joint 9, and a third support member 10 in the form preferably of a bolt as shown in the drawing connects between the support members 7 and 8 and is in a position against the tube-roller mandrel, all these three members thus bearing against and supporting the tool housing. The tube roller cage on the end of the mandrel involves rollers usually somewhat coned, and of detail as desired and generally well known, and requiring no further description here. The support elements 7 and 8 are in turn anchored to the adjacent structure, here the wall 4 of the furnace. For such anchorage this wall is provided with lugs 11 which have openings or eyes in which angle-wise projections 12 of the ends of the members 7, 8 fit, the lugs 11 providing means in a series spaced to the tubes 3 to hold

2

said angle-wise projections 12. The tube roller mandrel is thus positioned between three support elements which are firmly inter-united and are anchored in compact relationship. It will be understood that the cover, not shown, which customarily fits over and is spaced from the header box 2 and fits against the furnace wall 4 is of course removed for placement of the equipment in the tube rolling operation.

The operation of the equipment is readily understood from the foregoing. With the assemblage of the tube roller mandrel in its supports 7, 8, 10 anchored to the adjacent structure the operator by the handles 14 holds the motor-driven mandrel with its roller-cage in position in the end of the tube to be rolled. And on completion of that tube, the support is moved around to the next and similarly anchored in the provided lugs 11, and so on, e. g., by removing the bolt pin 10, lifting the support members 7, 8 to free their projections 12 from lugs 11, and moving the supports 7, 8 around to the next tube and other lugs on the furnace wall.

Other modes of applying the principle of the invention may be employed, change being made as regards the details described, provided the features stated in any of the following claims, or the equivalent of such, be employed.

I therefore particularly point out and distinctly claim as my invention:

1. In means for positioning a rotary tool for rolling the end of a tube in a header adjacent an extending furnace casing, which tool has a driving motor with guide handles and a drive shaft mandrel housing projecting from said motor with a tube-roller on said shaft, a holder preventing the rotary tool from jumping which includes a guide in which the drive shaft mandrel housing is positioned for alignment with the tube to be rolled, having two support members between and against which the mandrel housing is located, a hinge-type joint connecting the members for allowing easy placement and removal, a joining member connecting the support members and forming a third support against the drive shaft mandrel housing, angle-wise projections on the free ends of said support members, and eyeleted lugs on the adjacent furnace casing in a series spaced to the tubes to hold said angle-wise projections.

2. In means for positioning a rotary tool for rolling the end of a tube in a header adjacent an extending furnace casing, which tool has a driving motor with guide handles and a drive shaft mandrel housing projecting from said motor with a tube-roller on said shaft, a holder preventing the rotary tool from jumping which includes a guide in which the drive shaft mandrel housing is positioned for alignment with the tube to be rolled, having swingably connected support members between and against which the mandrel housing is located, a third support against the drive shaft mandrel housing and connecting the said support members, angle-wise projections on the free ends of said supporting members, and eyeleted lugs on the adjacent furnace casing in a series spaced to the tubes to hold said angle-wise projections.

3. In means for positioning a rotary tool for rolling the end of a tube in a header adjacent an extending furnace casing, which tool has a driving motor with guide handles and a drive shaft mandrel housing projecting from said motor with a tube-roller on said shaft, a holder preventing the rotary tool from jumping which includes a guide in which the drive shaft mandrel housing is positioned for alignment with the tube to be rolled providing three support elements surrounding the mandrel housing, two being joined by a hinge-like joint and the third connecting between the said two support elements, and means on the adjacent furnace casing in a series spaced to the tubes to anchor the said two support elements.

4. In means for positioning a rotary tool for rolling the end of a tube in a header adjacent an extending furnace casing, which tool has a driving motor with guide handles and a drive shaft mandrel housing projecting from said motor with a tube-roller on said shaft, a holder preventing the rotary tool from jumping which includes a guide in which the drive shaft mandrel housing is positioned for alignment with the tube to be rolled, providing three support elements surrounding the mandrel housing, two being adjustably connected by a joint at one end and the other connecting as the third support between the said two support elements, and means in a series spaced to the tubes for holding the other ends of the latter elements to the adjacent furnace casing.
